UNITED STATES PATENT OFFICE.

FELIX GERTH, OF BERLIN-TEMPELHOF, GERMANY, ASSIGNOR TO C. LORENZ AKTIEN-
GESELLSCHAFT, OF BERLIN-TEMPELHOF, GERMANY.

MODULATION SYSTEM.

Application filed June 28, 1927, Serial No. 202,057, and in Germany July 5, 1926.

- The present invention has reference to high frequency generating systems for radio communication purposes comprising a high frequency alternator supplying a fundamental frequency and one or more iron-cored frequency transformers to raise said fundamental frequency to a higher operating frequency. In such a system it has become known to use an iron-cored auxiliary magnetized choke coil for modulating the high frequency currents to be radiated in the form of electric waves into space, in accordance with signals or speech to be transmitted. The iron-cored choke modulator to this end is inserted into a circuit carrying the high frequency signalling currents, preferably the antenna circuit or a preceding (e. g. intermediary) circuit. But there exist certain drawbacks with such an arrangement of an iron-cored choke modulator in connection with a generating system of the character in question, in that beat phenomena caused by conditions of instability may occur between the frequency transformer output circuit and a following load (intermediary or antenna) circuit giving rise to very undesired disturbances.
- It is the object of the present invention to overcome these inconveniences to which end a special independent resonant circuit is provided coupled in any known manner to the output (antenna) or a preceding circuit and which contains the modulator choke coil.
- My invention is illustrated by means of example by the accompanying drawing which may be referred to in connection with the following detailed disclosure in order to get a clear and precise statement of its exact features and working.
- Referring to the drawing, the reference numeral 1 designates a high frequency alternator working in a well-known manner upon a circuit (fundamental frequency circuit) comprising a self-induction coil 2, a capacity 3 and the winding 4 of an iron-cored high-frequency transformer 5. The output circuit of the frequency transformer is constituted by a capacity 6, tuning coil 7, coupling coil 8 and is tuned to and carries a frequency being a multiple of the transformer input (alternator) frequency. Coupled to the transformer output or multiplication circuit, as it is called too, is an intermediary circuit constituted by a capacity 9, tuning coil 10, and coupling coils 11 and 12.
- Electric oscillations are transferred from the intermediary circuit to the radiating circuit comprising an ordinary antenna earth system with antenna 13, antenna loading coil 14, coupling coil 15 and earth connection 16. The iron-core of the frequency transformer 5 is dimensioned to be saturated by a fractional part only of the peak value of the fundamental (alternator) current. The self-induction 2 of the fundamental frequency circuit is given such a value with respect to the capacity 3, that by virtue of the saturation of the core and the corresponding alteration of its magnetic permeability the tuning of the fundamental circuit is periodically changed from a condition of resonance to a condition of non-resonance (critical resonance). The magnetic flux of the core changes suddenly each half-cycle from its positive to its negative saturation value. Short tension peaks are periodically generated at the terminals of the transformer winding and follow each other at regular intervals which produce by shock excitation damped wave trains of the natural frequency of the secondary circuit 4, 6, 8, 7 (e. g. 13-fold the fundamental frequency). By virtue of the regularly occurring impulses quickly following each other a practically undamped wave is produced. However, in the case of an iron-cored modulator coil being inserted in the antenna, or a preceding circuit, conditions of instability during the operation of the choke coil may arise giving rise to beat phenomena between two such circuits resulting specially in disturbing singing noises. The chief reason for that consists in that by reaction of the circuit containing the choke coil upon the transformer secondary (multiplication) circuit conditions in the saturation of the transformer iron-core are altered in a manner to introduce conditions of instability in the system. This may occur during the adjusting of the choke coil respectively its correct auxiliary current as well as during operation when altering its effective resistance in accordance with signals to be transmitted by controlling its D. C. magnetizing current. These drawbacks are avoided or at least minimized to a practically sufficient degree according to this invention by inserting the

modulator choke coil 17 into a special independent circuit coupled with the antenna circuit and consisting of a variable capacity 19 and a coupling coil 18 coupled with the 5 antenna self-inductance 15. 20 designates the high-frequency winding of the choke device, 21 its D. C. controlling winding connected to a microphone 23 in series with a speech current battery 22. The auxiliary or 10 "modulation" circuit 18, 19, 20 may also be connected to the antenna circuit or the intermediary circuit by means of a capacitive or conductive coupling, though the arrangement represented by the drawing has practically proved to be the most advantageous. 15

What I claim is:

1. A radio transmission system of the character described comprising in combination a circuit carrying a fundamental frequency, an iron-cored high-frequency transformer for raising said fundamental frequency to a useful higher operating frequency, a load or antenna circuit being in operative relation with the transformer output circuit and an auxiliary resonant circuit 20

being in coupling relationship with a circuit carrying high-frequency currents and containing an iron-cored auxiliary magnetized choke device for modulating the high frequency currents in accordance with signals 30 to be transmitted.

2. A radio transmission system of the character described comprising in combination a high-frequency alternator generating currents of a fundamental frequency, an iron-cored high-frequency transformer supplied by said alternator and carrying in its output circuit currents of a frequency being a multiple of said fundamental frequency, an antenna load circuit being in operative 35 relation with said transformer output circuit and an iron-cored choke device inserted into a resonant circuit being in coupling relationship with said antenna circuit to modulate the high-frequency currents in accordance with signals to be transmitted. 40

In testimony whereof I have affixed my signature.

FELIX GERTH.
